UNITED STATES PATENT OFFICE

STEPHEN A. STAEGE, OF PITTSBURGH, PENNSYLVANIA, ASSIGNOR TO WESTINGHOUSE ELECTRIC & MANUFACTURING COMPANY, A CORPORATION OF PENNSYLVANIA

NEON-LAMP STROBOSCOPE

Application filed August 14, 1929. Serial No. 385,916.

My invention relates to stroboscopic devices and more particularly to light-producing apparatus therefor.

My invention has for an object to provide means for intermittently producing a light in accordance with the alternations of an alternating source of electro-motive force.

Another object of my invention is to provide means for producing a brilliant light during a sharply defined predetermined fractional period of the time of each voltage alternation of an alternating electro-motive force.

My invention is particularly applicable to stroboscopes for use in connection with sectional paper-machine drives but it is also useful for any rotating or vibrating apparatus the speed of which is synchronous or substantially synchronous with the alternating-current source.

My invention is also applicable to all types of stroboscopes wherein a clear, sharp and brilliant light for a well defined predetermined lighting period is desirable.

It is well known that neon and similar gas-filled lamps have a critical lighting voltage which makes them useful for stroboscopic lighting purposes, especially in connection with an alternating electromotive force. When energized from an alternating-current source, however, the lamp is lighted during the entire time that the voltage wave is passing over its crest. That is, as the voltage increases to the critical lighting voltage of the lamp, the latter lights and continues lighted until the voltage decreases to the shut-off voltage of the lamp. This may be an appreciable length of time, because the voltage wave is flat near its crest.

Attempts have been made to so "peak" the voltage wave as to decrease the light period, but this requires special apparatus. By means of my invention, however, a brilliant light, having a shorter period of duration than either of the above, is produced with the aid of only ordinary apparatus, such as a resistor and a condenser in addition to the usual neon lamp.

A brilliant light having a short duration is essential in stroboscopic work to prevent

blurring of the moving objects to be observed, and to produce a sharp image to thereby increase the accuracy of position-time measurements.

The accompanying drawing illustrates my invention and its mode of operation.

In the drawing,

Figure 1 is a schematic diagram of a stroboscopic light-producing device constructed in accordance with my invention.

Fig. 2 is a graphic representation of the voltage curve, plotted against time, of the device shown in Fig. 1, and

Fig. 3 is a graphic representation of the visual luminosity of the lamp of Fig. 1, plotted against time.

Referring to Fig. 1, the primary winding 2 of a voltage transformer 3 is connected in circuit relation with an alternating-current generator 4 by means of conductors 5 and 6. A variable resistor 7 is inserted in series with the conductor 5 in order to provide means for adjusting the voltage applied to the primary winding 2 of the transformer.

The secondary winding 8 of the transformer 3 is connected to a neon or other gas-filled lamp 9 by means of conductors 10 and 12. A resistor 13, of relatively high resistance, is inserted in series with the conductor 10 and the neon lamp 9 for producing a proper voltage across the terminals of the lamp. A condenser 14, of suitable capacity, is shunted across the terminals of the lamp, as indicated.

The operation of the device is as follows: When the primary winding 2 of the transformer 3 is connected across the supply mains 5 and 6, as shown, the lamp 9 is not effectively energized, until the voltage impressed upon its terminals has reached the critical lighting voltage for which the lamp was designed, this does not occur until sufficient current has passed through the resistor 13 to charge the condenser 14 up to this breakdown voltage. When this voltage is reached, a break-down occurs across the lamp terminals, and a current, limited in magnitude by the resistance of the lamp circuit, flows until the voltage has dropped to a critical shut-off point.

The resistance of the resistor 13 and the capacity of the condenser 14 are so proportioned that the condenser is fully charged only after the secondary voltage V_1 (Fig. 2) has passed its maximum value and has closely approached the minimum breakdown voltage V_b of the neon lamp. As the secondary voltage reaches this critical value V_b , the lamp breaks down and passes its maximum current C limited only by the lamp and condenser circuit, (Fig. 3) lighting the lamp 9 until the shut-off voltage V_s of the lamp has been reached.

The critical lighting-voltage zone of the lamp is defined as the region of the curve V_1 in Fig. 2 bounded by the lines through the points designated as V_b and V_s , and parallel to the time axis. It is to be noted that the lamp has a critical lighting-voltage zone for every half cycle of the source.

Since the period of time occupied by the discharge between the points V_b and V_s , that is within the critical lighting-voltage zone, is extremely small, the lamp emits a sharp brilliant light.

The condenser 14 acts like a reservoir, taking a voltage V_2 , while the voltage V_1 is increasing and decreasing, until the voltage V_2 attains the value of the critical breakdown voltage, V_b of the lamp, at which time, the condenser 14 discharges through the lamp until the shut-off voltage V_s of the lamp is reached. This action takes place at every half-cycle producing a brilliant light having well defined time limits for extremely short periods of each alternation of voltage.

The voltage V_1 , of the secondary winding 8 of the transformer 3 is so adjusted by means of the variable resistor 7 that it has a maximum instantaneous value substantially higher than the breakdown voltage of the lamp.

It will be obvious, to those skilled in the art that, in some cases, the transformer 3 may be omitted without affecting the operation of the device; that is, in those cases where the voltage at the terminals of the alternating-current source is of the proper magnitude.

By means of my invention, a sharp and distinct light for short predetermined periods of each voltage alternation is cyclically produced by a neon lamp in accordance with the frequency of an alternating-current generator.

It will also be apparent that, regardless of the voltage of the source 4, an operator may adjust the voltage V_1 by means of the resistor 7, to produce a sharp and adequately illuminated image of the observed moving object.

I have described the principle of operation of my invention, together with the apparatus that I now consider to represent the best embodiment thereof, but it is to be un-

derstood that the apparatus shown and described is only illustrative and that the invention may be embodied in other specific means.

I claim as my invention:

The combination with a source of electrical energy having a substantially sinusoidal wave form and a lamp having a critical lighting-voltage zone, of means for lighting said lamp for a fraction of the time of each voltage alternation of said source, including means for storing energy from said source over the peak of the wave until the critical lighting voltage zone of said lamp is reached and then discharging said stored energy through said lamp until the critical lighting-voltage zone is passed.

In testimony whereof, I have hereunto subscribed my name this 8th day of August, 1929.

STEPHEN A. STAEGE.
